COMBINATION FIXTURE AND WALL UNIT
WITH JOINTS AND TRIMS THEREFOR

Jabez Herbert Norris, Covington, Ky.

Application November 27, 1936, Serial No. 113,081

13 Claims. (Cl. 189—1)

This invention relates to improvements in building construction and more particularly to combination fixture and wall units with joints and trim therefor.

5 In the building industry, trouble has been experienced in securing or anchoring heavy fixtures, such as bathtubs, sinks and lavatories to the walls or floors of a room in a manner to prevent the formation of cracks or crevices at the junctures 10 of the various fixtures with the walls or floors upon shrinkage or settling of the house. In the case of tiled walls or floors in bathrooms and kitchens, which are ordinarily exposed to quantities of water, these cracks between the fixtures 15 and the walls or floors become particularly objectionable and require periodic treatments in order to prevent leakage of water therethrough and damage to other portions of the building.

The primary object of the invention is the provision of a combination fixture and wall unit 20 wherein one or more fixtures are inseparably associated with a wall-forming panel or wainscot.

Another object of the invention is to provide a combination fixture and wall unit which may be readily carried through standard size doorways 25 in existing buildings and positioned and installed therein by a small number of workmen, in addition to being suitable for new construction.

A further object is to provide a combination 30 fixture and wall unit for rooms and which may be rigidly installed in a manner tending to evenly distribute its load over a considerable area of the floor and wall structure of the room whereby to relieve excessive strain on portions of the floor 35 or wall structure, it being often necessary to weaken certain load bearing members of rooms, such as bathrooms and kitchens, as by providing cuts or notches therein for the accommodation of plumbing pipes.

40 A further object of the invention is to provide a combination fixture and wall unit having an improved flanged base and an improved floor mold.

Still another object of the invention is to provide a panel or wainscot construction for association with the lower portion of a wall and having an improved finishing mold for the upper edge of 45 the panel.

A still further object is to provide a supporting bar for towels and the like and improved means 50 for attaching the bar to a panel or wainscot.

Other objects and advantages of the invention will be apparent from the following detailed description, taken in connection with the accompanying drawings, forming a part of this specification and in which:—

Figure 1 is a perspective view of a fixture-containing room illustrating the application of the improved building construction units thereto, certain portions of the room being shown broken away and in section to illustrate details thereof. 5

Figure 2 is a perspective view similar to Figure 1 but looking at a different angle.

Figure 3 is a perspective view of a combination bathtub and wall unit shown in Figures 1 and 2.

Figure 4 is a perspective view of a combination 10 lavatory and wall unit shown in Figures 1 and 2.

Figure 5 is a vertical sectional view taken on the line 5—5 of Figure 2.

Figure 6 is a vertical sectional view taken on the line 6—6 of Figure 1. 15

Figure 7 is a plan view of the room shown in Figures 1 and 2.

Figure 8 is a fragmentary perspective view 20 showing details of a panel and finishing mold preferably forming a part of the improved building construction.

Figure 9 is a fragmentary vertical sectional view showing a preferred application of the panel and finishing mold to a wall supporting member.

Figure 10 is a horizontal sectional view of a 25 supporting bar for towels and the like and showing improved means for attaching the bar to a panel.

In the drawings, which show preferred and modified forms of the invention, and wherein 30 similar reference characters denote corresponding parts throughout the various views, the letters A and B may respectively designate floor and wall supporting means cooperating to support a pier type lavatory fixture and wall unit C, a recessed 35 type bathtub fixture and wall unit D and panel wall units E which may be joined together in end to end relation and provided at their upper edges with a molding F, while G may designate a floor carried by the floor supporting means, and 40 H a wall carried by the wall supporting means above the molding F.

The floor and wall supporting means A and B 45 preferably may comprise a plurality of evenly spaced horizontally disposed joists 10 and vertically disposed studs 11 respectively.

Referring to the combination lavatory fixture and wall unit C shown in Figure 4, it may comprise a lavatory portion 12 of the outwardly projecting pier type having exposed side walls 13 as 50 well as a front wall 14 forming a depending skirt 15 extending downwardly from a substantially horizontal bowl-containing top surface 16, the unit C further comprising a panel portion 17 extending upwardly from the top surface 16 and 55

laterally of the side walls 13 of the lavatory portion. Along the lower edge of the combination fixture and wall unit C is a horizontally disposed supporting flange 18 provided with a series of spaced apart screw or nail receiving apertures 19. In spaced parallel relation above the flange 18 is an integral floor mold 20 including a substantially horizontal floor-contacting flange 21. Along the upper marginal edge of the unit C a series of spaced apart apertures 22 is provided. Preferably, the panel portion 17 is of a height to line the lower portion of a room and of a length to extend from corner to corner thereof, and in certain cases, the panel portion 17 may include 15 at one end thereof an angular extension 23 forming a part of an adjacent wall. At the other end of the panel, the flange 18 and the floor mold 20 may terminate in a mitered end 24 forming a connecting element 25 in the panel above and 20 extending beyond the mitered end. Suitably positioned recessed tumbler holding or soap containing receptacles 26 may be provided in the panel portion 17. On the reverse side 27 of the panel are secured one or more pairs of spaced apart 25 vertical reinforcing channels 28 including apertures 29 aligning with apertures 30 in the panel. In Figure 10 is shown a U-shaped supporting bar 31 having flared tubular ends 32 in which are embedded a pair of internally threaded cylindrical 30 inserts 33 cooperating with the flared ends to form seats 34 for a pair of cushioning washers 35. Extending through the apertures 29-30 and the cushioning washers 35 from the reverse side 27 of the panel and threading into the inserts 33 are 35 suitable cap screws 36. On the front wall 14 of the lavatory portion, a suitably hinged access door 37 may be provided.

As for the combination bathtub fixture and wall unit D shown in Figure 3, it may comprise a 40 tub portion 38 of the recessed type having an exposed front wall or skirt 39 depending downwardly from a substantially horizontal upper surface 40 provided with a concave tub-forming portion 41, the unit D further comprising a panel portion 45 42 extending upwardly from the upper surface 40 at its rear extremity 43 and side extremities 44 forming rear and side walls 45 and 46 respectively. In addition, the panel portion 42 may extend laterally from the front wall or skirt 39 at its end extremities 47 forming walls 48 and 49. 50 If desired, the wall 49 may include an angularly extending portion 50 provided with a suitably hinged access door 51 and a recessed paper holder 52. The rear wall 46 may be provided 55 with a recessed soap container 53 and a U-shaped supporting bar 54 having its ends affixed to the panel as by welding. Along the lower edge of the combination fixture and wall unit D is a horizontally disposed supporting flange 55 provided 60 with a series of spaced apart screw or nail receiving apertures 56. In spaced parallel relation above the flange 55 is an integral floor mold 57 including a substantially horizontal floor-contacting flange 58. Along the upper marginal edge 65 of the unit D a series of spaced apart apertures 59 is provided. The panel portion of the unit D preferably is of a height to line the lower portion of a room and of a length to extend from corner to corner thereof. At the ends of the panel portion 42, vertical channel-forming connecting elements 60 and 61 may be provided and in order to permit other panels to be connected thereto, the ends of the flange 55 and the floor mold 57 70 may be terminated short of the connecting ele-

ments 60 and 61 as by a butt end 62 and a mitered end 63 respectively.

Panel wall units E may be utilized in conjunction with the combination fixture and wall units as shown in Figures 1, 2, and 7. The vertically disposed panel units 64 and 65 are substantially similar in that their lower edges are each provided with a horizontally disposed supporting flange 66 having a series of screw or nail receiving apertures 67. Also, each unit is provided, in parallel relation above the flange 66, with an integral floor mold 68 including a substantially horizontal floor contacting flange 69. The panel unit 64 may be provided at one end with a vertical fin-like extension 70 beyond the mitered end 71 of the flange and floor mold. The other end 72 of the panel unit 64 may terminate in a vertical plane, if desired. The panel unit 65 may be provided at one end with a vertically disposed channel 73 and the opposite end may include an 10 outwardly offset vertical fin-like extension 74. The panel units E preferably are of a height corresponding to the height of the combination fixture and wall units C and D.

Referring now to Figures 8 and 9, it will be seen that the upper edge of the unit D carries the finishing molding F, having a depending rear flange 75 which is provided with upwardly extending notches 76 corresponding in spacing to the apertures in the panels. The molding F may 30 include a front wall 77 depending from a relatively wide horizontal top portion 78 and adapted to cover and conceal the openings in the panels. If desired, the molding F may also include horizontal and vertical walls 79 and 80 extending inwardly and upwardly from the lower edge of the front wall 77. Similarly, the units C and E may be provided along their upper edges with suitable lengths of molding F.

Due to the convenient size of the units C, D, 40 and E, they may be manufactured, crated, transported and installed in much the same manner as separate fixtures, while permitting of mass production in a factory of the major portions of fixture containing rooms, such as bathrooms and 45 kitchens; and at the same time avoiding the difficulty of transporting a completely assembled room unit from the factory and installing it in an existing or partially completed structure. The units C, D, and E may be joined together in 50 end to end relation by inserting the vertically disposed fin-like extensions thereof into the vertically disposed channel-forming members of adjacent units as shown in Figures 1, 2, and 7. The bottom flanges 18, 55, and 66 of the units C, 55 D, and E may be either nailed or screwed to the floor supporting members 10, and the upper edges may be secured in spaced relation to the wall supporting members 11 as by suitable screws 18 and spacing washers 19 shown in Figure 9. When the molding F is brought down over the upper edges of the units, the depending flange 75 will occupy the space reserved by the washers 19 between the upper marginal edges 11, with the washers 19 positioned one in each notch 76, it being understood that the notches 76 are spaced to correspond with the spacing of the wall supporting members 11.

As shown in Figures 5 and 6, the floor G may be carried by the floor supporting means A and preferably it may extend between the bottom flanges and the floor moldings of the various units, the upper surface of the floor contacting 70 75

the undersides of the floor moldings and providing a seal therealong.

The wall H carried by the wall supporting means above the molding F may be of any suitable construction and may at its lower edge rest upon the molding and hold the same in place. It will be seen that where the molding F extends from corner to corner of the room and is mitered at its ends, as shown in Figure 8, it will act as a strut between opposite walls and will also tend to increase the rigidity of the panel or panels from which it is mounted.

The units C, D and E may be produced by any suitable method, such as casting or pressing. Obviously, the lavatory, bathtub or accessory fixtures may be first separately formed and subsequently welded or otherwise combined with suitable wall panels into a single unit at the factory and preferably prior to the application of a porcelain, enamel, or other suitable coating or finish. The wall panels may simulate the appearance of tiling, if desired. In order to provide for the installation of a medicine cabinet 80, a suitable notch 81 may be formed in the top edge of any of the units, such as the lavatory unit C.

Various changes may be made to the shape, size and arrangement of parts herein shown and described, without departing from the spirit of the invention or the scope of the following claims.

I claim:

1. A combination fixture and wall unit comprising a fixture including a supporting skirt and a wainscot integral with the fixture and including fixture-supporting portions extending upwardly from and laterally of the fixture and defining an opening at the rear of the fixture.
2. A combination fixture and wall unit comprising a fixture having a skirt forming a base, and a wainscot integral with the fixture, said wainscot extending upwardly of the fixture and laterally of the skirt and defining an opening at the rear of the skirt.
3. A combination fixture and wall unit comprising a wainscot portion provided with an opening, said wainscot portion having a supporting flange along its lower edge and a fixture portion having a plurality of walls integrally joined to the wainscot portion adjacent the opening whereby the fixture portion conceals the opening.
4. A combination fixture and wall unit comprising a fixture including a skirt, a wainscot extending laterally of the skirt and integral therewith and a continuous supporting flange along the lower edges of the skirt and wainscot.
5. A combination fixture and wall unit comprising a fixture provided with an integral wainscot portion, said wainscot portion having a supporting flange along its lower edge and an integral floor molding in spaced parallel relation above the flange.
6. A combination fixture and wall unit comprising a fixture including a skirt, a wainscot extending laterally of the skirt and integral therewith, a continuous supporting flange along the lower edges of the skirt and wainscot, and a continuous floor molding integral with the skirt and wainscot and in spaced parallel relation above the flange.
7. A combination fixture and wall unit comprising a fixture provided with an integral wainscot portion extending laterally and upwardly

of and in at least partially encircling relation to the fixture and defining an opening behind the fixture, said wainscot portion being provided along its upper edge with a series of openings adapted to facilitate fastening of the upper edge 5 of the wainscot portion, and having a supporting flange along its lower edge.

8. In a room construction, floor supporting means, wall supporting means, a plurality of vertically disposed panels each having a flanged 10 lower edge resting on the floor supporting means, said panels being joined together in end to end relation adjacent the wall supporting means, means securing said panels at their upper edges to said wall supporting means, whereby said 15 panels form a wainscot for the lower portion of the room, at least one of said panels including an integral fixture having a downwardly extending skirt terminating at its lower edge in the flanged lower edge of the panel. 20

9. In a wainscot wall, a wall supporting member, a panel, means securing the panel along its upper edge in spaced adjacent relation to the wall supporting member and a molding covering the upper edge of said panel, said molding including a depending flange extending between the panel and the supporting member. 25

10. In a wainscot wall construction, a wall supporting member, a panel having an aperture along its upper marginal edge, spacing means 30 between the panel and the supporting member, and provided with an aperture aligning with the aperture in the panel, panel fastening means extending through said apertures and carried by the wall supporting means, and a molding covering the upper edge of said panel, said molding including a depending flange extending between the panel and the supporting member, the depending flange being provided at its lower edge with an upwardly extending notch receiving said 40 spacing and fastening means.

11. In a wainscot wall construction for a multi-cornered room, wall supporting means for a plurality of intersecting walls defining the room, a series of vertically disposed panels in end to end 45 relation, means securing said panels in inwardly spaced adjacent relation to the wall supporting means whereby to form intersecting interior wall surfaces of the room, and a plurality of intersecting moldings each including a depending flange 50 extending between a panel and the wall supporting means, at least one of said moldings extending from corner to corner of the room and being mitered between adjacent moldings.

12. A combination fixture and wainscot unit 55 comprising a wainscot portion having an opening and a fixture portion including supporting walls integral with and projecting from the wainscot portion adjacent the edges of the opening whereby a concealed roughing-in space is provided behind the fixture portion. 60

13. A combination fixture and wainscot unit comprising a wainscot portion provided with an opening extending upwardly from its lower edge 65 and a fixture portion including walls integral with and projecting from the wainscot portion adjacent the edges of the opening, at least one of the walls of the fixture portion terminating in a plane common to the lower edge of the wainscot portion and whereby a concealed open space is 70 provided beneath and behind the fixture portion.
